United States Patent Office

Des. 181,221
Patented Oct. 15, 1957

181,221

ARMORED VEHICLE

Alexander S. Moorehead, North San Juan, Calif.
Application February 13, 1957, Serial No. 44,860

Term of patent 14 years

(Cl. D14—3)

Fig. 1

Fig. 2

Fig. 3

I claim:

The ornamental design for an armored vehicle, as shown.
